UNITED STATES PATENT OFFICE.

EMMA RHADER, OF ASHLAND, OHIO.

DESIGN FOR A GLOBE.

43,969.

Specification for Design.

Patented May 6, 1913.

Application filed December 20, 1911. Serial No. 667,054. Term of patent 7 years.

To all whom it may concern:

Be it known that I, EMMA RHADER, a citizen of the United States, residing at Ashland, in the county of Ashland and State of Ohio, have invented a new, original, and ornamental Design for Globes, of which the following is a specification, reference being had to the accompanying drawings, forming a part thereof.

The figure is an elevation of a globe showing my new design.

I claim:

The ornamental design for a globe as shown.

EMMA RHADER.

In the presence of—

P. E. HOLBEN,
MARGARETTA CLUGSTON.

Copies of this patent may be obtained for five cents each, by addressing the "Commissioner of Patents, Washington, D. C."
